UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE.

1,190,319.

Specification of Letters Patent. Patented July 11, 1916.

Application filed November 16, 1912. Serial No. 731,892.

To all whom it may concern:

Be it known that I, ADAM H. PRENZEL, a citizen of the United States, residing at Halifax, in the county of Dauphin and State 5 of Pennsylvania, have invented certain new and useful Improvements in Shoes, of which the following is a specification, reference being had therein to the accompanying drawing.

10 This invention relates to an improvement in shoes.

The primary object of the present invention is the provision of a strong and durable shoe which in appearance is not inferior to 15 the shoes of the well known welt or turned types, but which is of such a construction that it can be manufactured more economically and easily than the shoes of these types as made according to the present methods.

20 Other objects of the invention will be apparent from the detailed description hereinafter when read in connection with the accompanying drawings, forming a part hereof, wherein a convenient embodiment of 25 the invention is illustrated, and wherein like characters of reference refer to similar parts in the several views.

The novel process of making shoes herein disclosed is not claimed herein but is claimed 30 in my co-pending application Serial No. 731,894, filed of even date herewith, upon which application Letters Patent No. 1,159,083 were granted November 2, 1915, while similarly the novel shoe sole herein 35 disclosed is not claimed herein but is claimed in my co-pending application Serial No. 731,893, also filed of even date herewith.

In the drawings: Figure 1 is a top plan view of an unfinished shoe embodying the 40 present invention. Fig. 2 is a side elevation of the completed shoe; Fig. 3 is a sectional bottom plan of the upper and portions of the insole; Fig. 4 is a bottom plan of the insole; Fig. 5 is a top plan of the outsole; Fig. 6 is a cross section through the outsole; Fig. 7 is a cross section through the insole and Fig. 8 is an enlarged section of the 45 various parts in their associated condition when the shoe is completed.

50 Referring now more particularly to the drawings, the improved shoe comprises an upper A, an outer sole B, and an inner sole C. The outer sole B is provided with a

channel b around the edge of the front portion thereof, the ends of said channel terminating adjacent to the heel portion of the sole. The channel b is formed by cutting out a portion of the outer sole with any suitable implement, the formation of such channel providing a vertical shoulder b' 55 extending around the forward portion of the outer sole B. The base of the channel or recess b inclines downwardly from the shoulder b', to the outer edge of the sole to a slight extent for a purpose to be hereinafter more particularly set forth, and the base of said channel or recess, at one end thereof, merges into the upper surface of the heel portion of the outer sole.

The upper A, which may be of any suitable form, is provided with short inwardly extending cuts a a in its lower edge on each side thereof, said cuts overlying, when the upper is positioned over the outer sole, the end portions of the channel or recess b 75 formed therein.

The inner sole C is of such a size that when superposed on the outer sole B, the outer portion thereof will project outwardly beyond the shoulder b' of the channel or recess in the outer edge of the outer sole and will overlie the base of such channel or recess. The sides of the inner sole C have secured thereto in any suitable manner, flaps or welts c c of fabric or other strong 85 flexible material, such flaps extending conveniently from the shank of the inner sole to points adjacent the front thereof.

In making the shoe the inner sole is placed directly upon the outer sole and the side 90 flaps or welts c c thereof are tucked inwardly so as to overlie the vertical shoulder b' and the bottom of the channel or recess b which is formed in the outer portion of the outer sole B. The lower edge of 95 the upper, forward of the nicks a a therein, is turned outwardly as at a', and in securing the upper in position, the outwardly extending portion a' thereof is tucked into the space which is provided between the 100 outer portion of the inner sole and the base of the channel b which is formed in the outer edge of the outer sole so that a part of the outwardly extending portion of the upper will directly overlie the vertical 105 shoulder of the channel or recess b in the

outer sole while the remainder of said outwardly turned portion a' of the upper will rest directly upon the bottom of said channel or recess. The tucked-in part of the 5 outwardly turned portion a' of the upper is secured directly to the outer sole by means of lasting staples or other fastening means E which pass through the lower edge of the upper and into the vertical shoulder 10 b' of the channel or recess which is formed in the outer edge of the outer sole. The vertical shoulder b' of the channel or recess b in the outer portion of the outer sole provides a solid backing against which the 15 lower edge of the upper may be secured by the lasting staples E , which staples are allowed to remain in position and become a permanent part of the sole attaching means. It will be seen that the lasting staples 20 which are utilized to connect the upper to the outer sole pass through the strips of fabric $c c$ which are secured to the sides of the inner sole C as well as through the upper and that by reason of this fact, such staples 25 or other fastening means serve to connect the inner sole to the outer sole in a strong durable manner so as practically to preclude its separation therefrom. The utilization of securing flaps or strips of this character in 30 connection with the in-sole is also of considerable value as it enables the use of a cheaper material for making in-soles, which materials could not, themselves, be properly secured in position by stitching or fastening means.

The lower edge of that portion of the upper in the rear of the cuts $a a$ therein is turned inwardly and secured by nails or other suitable fastening means to the underside of the inner sole C . The outwardly turned portion a' of the upper which overlies the bottom of the channel or recess b in the outer sole B , is next trimmed so that the edge thereof will be positioned inwardly 45 of the edge of the outer sole and a portion of the bottom of the channel or recess b of the outer sole will be exposed.

B' designates a welt strip which is adapted to overlie the outwardly extending portion a' of the upper and the exposed portion of the bottom of the channel or recess b of the outer sole. The welt strip B' is forced inwardly between the portion of the upper which is tucked inwardly between the inner 55 and outer soles, the inner edge of said welt strip being adapted to overlie the lasting staples which pass through the upper into the shoulder b' of the channel or recess b in the inner sole, and thus serves to prevent withdrawal of the staples. With the welt strip B' in this position, it is secured to the outer edge by a row of stitching b^2 or other fastening means which passes through the welt strip, the outer sole and the interposed portion 60 of the upper, as well as those portions

of the flaps $c c$ of the inner sole which overlie the base of the channel or recess b in the outer sole.

The welt strip B' is of a length to completely fill the channel or recess b in the outer sole of the shoe and is conveniently of such width that when secured in position, the outer edge thereof will lie flush with the outer edge of the outer sole, thus simplifying the finishing of the sole of the shoe. 70 When the welt strip is secured in position it is drawn tightly into engagement with the exposed portion of the bottom of the recess b in the outer sole so that the joint between the welt strip and the outer sole 75 will be practically invisible. The lower face of the welt strip B' is preferably beveled slightly, said strip being thinner at its thinner edge than at its outer edge. This construction facilitates the forcing of the welt strip inwardly between the inner and outer soles. 80

While any well known form of welt strip may be used to form the shoe as above described, I prefer to use for the purpose of simplicity and economy of manufacture, a welt strip which is formed as a part of the outer sole, and to this end the portion of the outer sole which is removed to form the channel or recess b therein is utilized as the 90 welt strip, such portion being detached from the sole at one end of the groove or channel only. Simultaneously with the removal of the welt strip B' from the outer sole to form the channel or recess b therein, a small 95 strip is cut from the outer edge of the welt strip so that said strip will be of slightly less width than the channel or recess which is formed along the outer edge of the outer sole. By making the welt strip of less width than the channel in the outer sole, provision is made for the thickness of the upper which overlies the shoulder at the inner edge of the channel or recess, so that when the 100 welt strip is secured in position, the outer edge thereof will lie flush with the outer edge of the outer sole, which, as has been before stated, facilitates the finishing of the outer sole. In order to insure that the outer edge of the welt strip will lie flush with the outer edge of the sole throughout its length, the portion of the welt strip which surrounds the toe of the shoe is made slightly narrower than the remainder thereof so as 105 to allow space for the accommodation of the tip of the shoe. As has been before stated, the bottom walls of the channel b in the outer sole and the underside of the welt strip B' are conveniently beveled, the outer edge 110 of the welt strip being of greater thickness 115 than the inner edge. This being the case, it will be seen that when a strip is cut from the outer edge of the welt strip, the thickest portion of the welt strip is removed which tends to prevent the formation of a sole hav- 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 ing a bulky appearance when the welt strip is secured thereto with the outer edge thereof of flush with the outer edge of said outer sole. With a shoe constructed in the manner above described, it will be seen that as the inner sole projects outwardly beyond the shoulder which forms the inner wall of the channel or recess in the outer sole, and as such sole is secured to the outer sole by the same fastening means which are utilized to secure the upper to the outer sole, the upper cannot be drawn inwardly to expose the joint at the inner edge of the welt, so that in appearance the shoe does not differ materially from the ordinary welt and turned shoes as at present manufactured, and at the same time by reason of the simplicity of the construction of the present shoe, and the small number of operations entailed in the manufacture thereof, it can be made much more economically than shoes of the types now manufactured.

In completing the shoe, the heel portion of the outer sole is fastened to the inner sole in any well known manner and if desired, any well known form of heel may be secured to the outer sole. In the drawing a spring heel shoe is illustrated and when the invention is utilized in connection with a shoe of this type the heel portion of the outer sole is preferably stamped outwardly to form the heel of the shoe and a filler of any suitable kind is interposed between the said stamped-out portion and the heel portion of the inner sole, the parts being fastened together in any well known manner.

While a convenient embodiment of the invention is illustrated in the accompanying drawings, it will be understood that the invention is not limited to the particular form and construction therein shown and that various changes may be made without departing from the spirit and scope of the invention as defined in the appended claims.

I claim:

1. In a shoe, an outer sole, an inner sole, means for securing the edge portion of the inner sole to the edge portion of the outer sole with the edge portion of said inner sole in spaced relation to said outer sole, an upper provided with an outwardly turned portion overlying the edge portion of the outer sole, a welt strip overlying the outwardly turned portion of the upper, the inner edge of said welt strip extending between the inner and outer soles, and fastening means connecting the welt strip, outer sole, and interposed portion of the upper.

2. In a shoe, an outer sole, an inner sole, means for securing the edge portion of the inner sole to the edge portion of the outer sole with the edge portion of said inner sole in spaced relation to said outer sole, an upper, a portion of the lower edge of said upper being tucked inwardly between the

inner and outer soles and the free edge of said portion being extended outwardly to overlie the edge portion of the outer sole, said inwardly tucked portion of the upper being also secured to the outer sole, a welt strip overlying the edge portion of the outer sole and the portion of the upper resting thereon, and fastening means connecting the welt strip, outer sole, and interposed portion of the upper.

3. In a shoe, an outer sole, an inner sole, means for securing the edge portion of the inner sole to the edge portion of the outer sole with the edge portion of said inner sole in spaced relation to said outer sole, an upper, a portion of the lower edge of said upper being tucked inwardly between the inner and outer soles, and the free edge of said portion being extended outwardly to overlie the edge portion of the outer sole, said inwardly tucked portion of the upper being also secured to the outer sole, a welt strip overlying the edge portion of the outer sole and the portion of the upper resting thereon, the inner edge of said welt strip extending between the inner and outer soles, and fastening means connecting the welt strip, outer sole, and interposed portion of the upper.

4. In a shoe, an outer sole, an inner sole positioned thereover, an upper, the lower edge of said upper being provided with an outwardly extending portion overlying the edge portion of the outer sole, a welt strip overlying the edge portion of the outer sole and the outwardly extending portion of the upper, said inner sole being provided with outwardly extending securing portions underlying the welt strip, and securing means for connecting the welt strip, outer sole, the interposed portion of the upper, and the securing portions of the inner sole.

5. In a shoe, an outer sole, an inner sole thereon, the outer edge of said inner sole being positioned inwardly of the outer edge of said outer sole, and said inner sole being provided with attaching portions overlying the edge portion of the outer sole, an upper provided at its lower edge with an outwardly turned portion overlying the edge portion of the outer sole, a welt strip overlying the edge portion of the outer sole and the outwardly turned portion of the upper, the inner edge of said welt strip extending between the inner and outer soles, and fastening means for connecting the welt strip, the outer sole, the interposed portion of the upper, and the attaching portions of the inner sole.

6. A shoe comprising an outer sole, an inner sole thereon, the outer edge of said inner sole being positioned inwardly of the outer edge of said outer sole and said inner sole being provided with attaching portions overlying the edge portion of the outer

sole, an upper provided at its lower edge with an outwardly turned portion overlying the edge portion of the outer sole, means for securing the outwardly turned portion of the upper, and the attaching portions of the inner sole to the outer sole inwardly of the outer edge of the inner sole, a welt strip overlying the edge portion of the outer sole and the outwardly turned portion of the upper, the inner edge of said welt strip extending between the inner and outer soles, and fastening means for connecting the welt strip, the outer sole, the interposed portion of the upper and the attaching portions of the inner sole.

7. In a shoe, an outer sole provided with a channel around the edge portion thereof, an inner sole overlying the outer sole, the edge portion of said inner sole projecting over the channel of the outer sole, an upper provided at its lower edge with an outwardly turned portion seated in the channel of the outer sole, a welt strip positioned in the channel of the outer sole and overlying the outwardly turned portion of the upper seated therein, the inner edge of said welt strip extending between the inner and outer soles, and securing means for connecting the welt strip, outer sole, and the interposed portion of the upper.

8. In a shoe, an outer sole provided with a channel in the upper surface thereof extending around its edge, said channel having a vertical inner shoulder, an inner sole overlying the outer sole and projecting over the channel formed in the edge thereof, an upper provided at its lower edge with an outwardly turned portion seated in the channel formed in the outer sole, a portion of said upper being tucked inwardly between the inner and outer soles, fastening means passing through the inwardly tucked portion of the upper into the vertical shoulders of the channel in the outer sole, a welt strip positioned in the channel in the outer sole and overlying the outwardly turned portion of the upper seated therein, the inner edge of said welt strip projecting between the inner and outer soles, and securing means connecting the welt strip, the outer sole, and the interposed portion of the upper.

9. In a shoe, an outer sole provided with a channel in the upper surface thereof extending around its edge, an inner sole overlying said outer sole, the edge portion of said inner sole projecting over the channel formed in the outer sole, said inner sole being provided with securing portions extending from the sides thereof, and overlying the channel in the outer sole, an upper provided at its lower edge with an outwardly turned portion seated in the channel formed in the outer sole, a welt strip overlying the outwardly turned portion of said upper, the

inner edge of said welt projecting between the inner and outer soles, and fastening means connecting the welt, outer sole, interposed portion of the upper, and the attaching portions of the inner sole.

10. In a shoe, an outer sole provided with a channel along its outer edge, said channel being provided with an inner vertical shoulder, an inner sole overlying said outer sole, the edge portions of said inner sole projecting over the channel formed in the outer sole, said inner sole being provided with attaching portions extending from the sides thereof into the channel in the outer sole, an upper provided at its lower edge with an outwardly turned portion seated in the channel in the outer sole, fastening means passing through the upper and the attaching portions of the inner sole and into the vertical shoulder of the channel in the outer sole, a welt strip overlying the outwardly turned portion of the upper, the inner edge of said welt strip projecting between the inner and outer soles and overlying the fastening means extending into the vertical shoulder of the outer sole, and means connecting the welt strip, the outer sole, the interposed portion of the upper, and the attaching portions of the inner sole.

11. In a shoe, superposed inner and outer soles, the edge portions of said soles being arranged in spaced relation and the outer edge of the inner sole being positioned inwardly of the outer edge of the outer sole, an upper, a portion of said upper being tucked inwardly between the edge portions of said inner and outer soles, and the free edge of said portion being extended outwardly to overlie the outer sole, fastening means connecting said upper to said outer sole inwardly of the outer edge of the inner sole, a welt strip overlying the outwardly extended portion of the upper, and fastening means connecting the welt strip, the outer sole, and the interposed portion of the upper.

12. A stitch-down shoe, comprising, in combination, an upper having an outturned sole attaching flange, an insole provided with a welt connected to the bottom face of said insole, an outsole, means for securing the upper to the outsole, said means serving also to secure the angle of the upper between the insole and the insole welt and to secure the insole welt to the outsole, a welt laid upon the outturned flange of the upper with its inner edge extending into the space between the edge of the insole and its welt, and means for securing the last named welt and upper to the outsole.

13. A stitch-down shoe, comprising, in combination, an upper having an outturned sole attaching flange, an insole provided with a welt attached to its bottom face, an outsole, means located in the angle of the

upper and between the insole welt and the edge of the insole for securing the upper in this location, a welt laid upon the outturned upper flange, and means for securing said 5 welt, the upper and the insole welt to the outsole.

14. A stitch-down shoe, comprising, in combination, an upper having an outturned sole attaching flange, an insole provided 10 with a welt attached to the bottom face of the insole, fastening means passing through the upper and said insole welt between said welt and the insole edge, an outsole, and means for securing said upper to said 15 outsole.

15. A stitch-down shoe, comprising, in combination, an upper having an outturned sole attaching flange, an insole provided 20 with a welt attached to its under face, an outsole, staples located in the angle of the upper and securing said angle of the upper to the outsole between the insole welt and the edge portion of the insole and serving 25 also to secure the insole welt to the outsole, a welt laid upon the outturned flange of the

upper and extending into the upper angle and covering the heads of said staples, and means for securing said welt, upper and insole welt to the outsole.

16. A stitch-down shoe comprising, in combination an upper provided with an outturned sole attaching flange, an insole located inside said upper, means for permanently securing the upper in lasted position directly to the outsole at points located between the outsole and insole, a welt laid upon said outturned portion of the upper and having its inner edge extending between the edge portion of the insole and the outsole, means for securing said welt and upper to the outsole, and means whereby said insole is also connected to the outsole by one of the aforementioned securing means.

In testimony whereof I affix my signature in presence of two witnesses.

ADAM H. PRENZEL.
